Primary Examiner — Barbara Fox*Assistant Examiner* — Katie S Mroczka(74) *Attorney, Agent, or Firm* — Rachel A. Kahler; Diederiks & Whitelaw, PLC; Annette M. Frawley, Esq.(57) **CLAIM**

The ornamental design for a shaped tortilla, as shown and described.

DESCRIPTION

FIG. 1 is a perspective view of a shaped tortilla; FIG. 2 is an end view of the shaped tortilla of FIG. 1; FIG. 3 is a side view of the shaped tortilla of FIG. 1; FIG. 4 is a cross-sectional view of the shaped tortilla of FIG. 1, taken along line 4-4 in FIG. 2; FIG. 5 is a top view of the shaped tortilla of FIG. 1; and, FIG. 6 is a bottom view of the shaped tortilla of FIG. 1. Where included, broken lines shown in FIGS. 1-6 illustrate portions of the shaped tortilla that form no part of the claimed design.
